UNITED STATES PATENT OFFICE.

HERMAN AXEL SCHEPELER, OF COPENHAGEN, DENMARK, ASSIGNOR TO A/S MEKANO,
OF COPENHAGEN, DENMARK.

SWITCH FOR THE CLOSING OF AN ELECTRIC CIRCUIT FOR A CERTAIN PERIOD.

1,348,746.

Specification of Letters Patent.

Patented Aug. 3, 1920.

Application filed October 30, 1918. Serial No. 260,348.

To all whom it may concern:

Be it known that I, HERMAN AXEL SCHEPELER, subject of the Kingdom of Denmark, residing at Copenhagen, Denmark, have invented certain new and useful Improvements in Switches for the Closing of an Electric Circuit for a Certain Period, of which the following is a specification.

This invention relates to electric light systems and more particularly to an automatic device whereby lights are lit for a predetermined time, the light circuit being automatically closed by a convenient switch and automatically opened at the end of the predetermined time.

The apparatus of the present invention is particularly well adapted for lighting halls or passage ways since it provides for automatically and without any manual operation breaking the circuit to extinguish the lights after a period of time which is ordinarily sufficient for the use of the lights.

A feature of this invention is the provision for a principal or light circuit of electro-magnetic means for closing the light circuit, an electric heating unit electrically connected with said electro-magnetic device, heat controlled means controlling by its expansion and contraction the lighting period and means operated by said heat controlled means for closing said light circuit independently of the closing of the circuit effected by the electro-magnetic device to permit the electro-magnetic device to assume a circuit opening position without opening the principal or light circuit. Thus by this means it is not left to the electro-magnetic device to maintain the circuit closed during the entire period.

The above and other advantages and advantageous results will be hereinafter more fully pointed out.

In the drawings:

Fig. 1 is a diagram showing one embodiment of the present invention.

Fig. 2 is a detail of the final circuit breaking switch, showing particularly the blowing magnet.

The conductors 1 and 2 are connected respectively to the positive and negative terminals of a suitable source of current. 3 indicates the buttons located in a convenient place for causing the lights 4 to be lit. The buttons 3 do not, however, directly close the circuit for the lights but operate to connect

an electro-magnet 14 to the circuit so that the electro-magnet will be energized by the current flowing through the coils thereof. In the circuit with the electro-magnet 14 and buttons 3 is provided a heating unit 5 in series with the electro-magnet 14. This heating unit preferably and as herein illustrated comprises a resistance wire inclosed in a bulb containing hydrogen and thus forms an incandescent lamp the radiant heat 60 of which acts on a member 6 which expands under the influence thereof. When the button 3 is operated to close the secondary circuit mentioned, the armature 13 is attracted by the core of the electro-magnet 14 and in 65 so moving a cross-bar 15 on the armature causes a contact 16 in the principal light circuit to be raised and engage the contact 18 connected to the negative terminal of the source of current and thus closing the circuit and lighting the lamps. Simultaneously, the cross-bar 15 of the armature causes a contact 17 to be raised and engage a contact 19 connected to the circuit containing the electro-magnet and the heating unit 70 75 and thus maintaining closed said circuit independently of the manually operated buttons 3. It will be seen therefore that it is merely necessary to push the button 3 and release the same the next instant, the electro-magnet maintaining its own circuit closed 80 85 automatically.

The apparatus remains in this condition during the heating and expansion of the heat controlled member 6 and until said 90 member 6 approaches the limit of its predetermined expansion when the duty of the electro-magnet to maintain the circuit closed is relieved. For this purpose the member 6 engages an arm 7 of a lever 8 having two 95 resilient and relatively longer arms formed therewith. On the end of the longest arm of the lever 8 is provided a contact 10 which when the member 6 approaches the predetermined limit of expansion engages with a 100 contact 12 connected to the lamp circuit and thus closes said circuit independently of the contacts 16 and 18, the negative terminal of the source of current being connected to the lever 8 through the heat controlled member 105 6. In this condition the lamp circuit will be maintained closed even though the electro-magnet is deenergized and the contacts 16—18 broken with the result that when said contacts 16 and 18 are broken there is 110

no resulting spark. The continued expansion of the heat controlled member 6 causes a contact 9 on the shorter of the two arms of the lever 8 to engage a contact 11 connected to the circuit containing the electro-magnet and the heating unit 5. Thus, when the contact 9 engages the contact 11 the electro-magnet and heating unit circuit is short circuited thereby deenergizing the 10 electro-magnet and rendering the heating unit 5 ineffective as a heating unit. This short circuiting of the electro-magnet and heating unit circuit takes place when the heat controlled member 5 reaches the limit 15 of its predetermined expansion and at this time the armature 13 returns to its circuit opening position. It should be noted however that this movement of the armature 13 does not cause the light circuit to be broken 20 since the period during which the lights remain lit in the present invention is not terminated when the heating member 5 reaches the limit of its predetermined expansion the period extending to the contracting period 25 of the heat controlled member 6. It should be noted that current passes through only one contact namely 10-12 at this time.

After a predetermined contraction of the heat controlled member 6, the spring connected to the lever 8 causes the contact 10 to be removed from the contact 12 thus breaking the circuit and extinguishing the lights.

In order to blow out the spark resulting from the breaking of the main lamp circuit by the contacts 10-12 there is provided a blow magnet 20 as shown in Fig. 2, the lines-of-force indicated by 21 are deflected downwardly by an armature 22 carried by the base plate 23 so that they will extend across the gap of the contacts 10-12 and thus extinguish the spark in the well known manner. It will be clear from the foregoing, that with the present apparatus the lamp circuit is closed instantaneously upon the 40 operation of the button 3 and independently of the heating unit or the heat controlled member therefore the periods during which the lights may be lit may be varied or regulated within wide limits without difficulty 45 by merely substituting different heating units without altering the rest of the circuit. This apparatus operates equally well for long or short periods of lighting.

Furthermore, by the utilization of both 55 the expansion and contraction of the heating member, current is not consumed by the heating unit and electro-magnet during part of the lighting period.

I claim as my invention:

60 1. In an electric light system, a light circuit; an electro-magnetic device for closing said light circuit; an electric heating unit electrically connected with said electro-magnetic device; heat-controlled means controlling by its expansion and contraction the 65

lighting period; and means operated by said heat-controlled means for closing said light circuit independently of the closing of the circuit effected by said electro-magnetic device to permit the electro-magnetic device to 70 assume a circuit opening position without opening the light circuit.

2. In an electric light system, a light circuit; an electro-magnetic device for closing said light circuit; an electric heating unit 75 electrically connected with said electro-magnetic device; heat-controlled means controlling by its expansion and contraction the lighting period; and means operated by the expansion of said heat-controlled means for closing said light circuit independently of the closing of the circuit effected by the electro-magnetic device to permit the electro-magnetic device to assume a circuit 80 opening position without opening the light circuit.

3. In an electric light system; a light circuit; an electro-magnetic device for closing said light circuit; an electric heating unit electrically connected with said electro-magnetic device; heat-controlled means controlling by its expansion and contraction the lighting period; means operated by the expansion of the heat controlled means for closing said light circuit independently of the closing of the circuit effected by the electro-magnetic device to permit the electro-magnetic device to assume a circuit 95 opening position without opening the light circuit; and means operated at the further 100 expansion of the heat-controlled means permitting the electro-magnetic device to assume said circuit opening position.

4. In an electric light system, a light circuit; an electro-magnetic device for closing 105 said light circuit; an electric heating unit connected electrically with said electro-magnetic device; heat controlled means controlling by its expansion and contraction the lighting period; means operated by the expansion of the heat controlled means for closing said light circuit independently of the closing of the circuit effected by the electro-magnetic device to permit the electro-magnetic device to assume a circuit opening 110 position without opening the light circuit; and means operated at the further expansion of the heat-controlled means for permitting the electro-magnetic device to assume said circuit opening position and 115 simultaneously rendering the heating unit ineffective.

5. In an electric light system, a light circuit; an electro-magnetic device for closing said light circuit; an electric heating unit 120 connected electrically with said electro-magnetic device; heat controlled means controlling by its expansion and contraction the lighting period; means operated by the expansion of the heat controlled means for 125 130

closing said light circuit independently of the closing of the circuit effected by the electro-magnetic device to permit the electro-magnetic device to assume a circuit opening 5 position without opening the light circuit; means operated at the further expansion of the heat-controlled means for permitting the electro-magnetic device to assume said circuit opening position and simultaneously 10 rendering the heating unit ineffective; and means for causing the circuit to be opened during and controlled by the contraction of the heat-controlled means.

6. In an electric light system, a light circuit; an electro-magnetic device for closing 15 said circuit; a secondary circuit for said electro-magnetic device; an electric heating unit connected in the secondary circuit with the electro-magnetic device; means for temporarily closing said secondary circuit to cause the electro-magnetic device and the heating unit to function; means operated 20 by said electro-magnetic device for closing said secondary circuit independently of said 25 temporary circuit closing means therefor; means operated by said electro-magnetic device for closing said light circuit; and heat-controlled means influenced by said heating unit and controlling by its expansion and contraction the lighting period.

7. In an electric light system, a light circuit; an electro-magnetic device for closing 30 said circuit; a secondary circuit for said electro-magnetic device; an electric heating 35 unit connected in the secondary circuit with the electro-magnetic device; means for temporarily closing said secondary circuit to cause the electro-magnetic device and the heating unit to function; means operated by 40 said electro-magnetic device for closing said secondary circuit independently of said temporary circuit closing means therefor; means operated by said electro-magnetic device for closing said light circuit; heat-controlled 45 means influenced by said heating unit and controlling by its expansion and contraction the lighting period; and means operated by said heat-controlled means for closing said light circuit independently of 50 the closing of the circuit by the means operated by the electro-magnetic device to permit the electro-magnetic device and the means operated thereby to assume its circuit opening position without opening the circuit.

8. In an electric light system, a light circuit; an electro-magnetic device for closing 55 said circuit; a secondary circuit for said electro-magnetic device; an electric heating 60 unit connected in the secondary circuit with the electro-magnetic device; means for temporarily closing said secondary circuit to cause the electro-magnetic device and the heating unit to function; means operated by 65 said electro-magnetic device for closing said

secondary circuit independently of said temporary circuit closing means therefor; means operated by said electro-magnetic device for closing said light circuit; heat-controlled means influenced by said heating 70 unit and controlling by its expansion and contraction the lighting period; and means operated by the expansion of the heat-controlled means for closing said lighting circuit independently of the closing of the 75 circuit effected by the means operated by the electro-magnetic device to permit the electro-magnetic device and the means operated thereby to assume a circuit opening position without opening said light circuit. 80

9. In an electric light system, a light circuit; an electro-magnetic device for closing said circuit; a secondary circuit for said electro-magnetic device; an electric heating unit connected in the secondary circuit with the electro-magnetic device; means for temporarily closing said secondary circuit to cause the electro-magnetic device and the heating unit to function; means operated by 85 said electro-magnetic device for closing said secondary circuit independently of said temporary circuit closing means therefor; means operated by said electro-magnetic device for closing said light circuit; heat-controlled means influenced by said heating unit and controlling by its expansion and contraction the lighting period; means operated by the expansion of the heat-controlled means for closing said light circuit independently of the closing of the circuit 90 effected by the means operated by the electro-magnetic device to permit the electro-magnetic device and the means operated thereby to assume a circuit opening position 95 without opening the light circuit; and means operated at the further expansion of the heat-controlled means for permitting the electro-magnetic device to assume said circuit opening position.

10. In an electric light system, a light circuit; an electro-magnetic device for closing 100 said circuit; a secondary circuit for said electro-magnetic device; an electric heating unit connected in the secondary circuit with the electro-magnetic device; means for temporarily closing said secondary circuit to cause the electro-magnetic device and the heating unit to function; means operated by 105 said electro-magnetic device for closing said secondary circuit independently of said temporary circuit closing means therefor; means operated by said electro-magnetic device for closing said light circuit; heat-controlled means influenced by said heating unit and controlling by its expansion and contraction the lighting period; means operated by the expansion of the heat-controlled means for closing said light circuit independently of the closing of the circuit effected by the means operated by the electro-magnetic de- 110

- vice to permit the electro-magnetic device and the means operated thereby to assume a circuit opening position without opening the light circuit; and means operated by the further expansion of the heat-controlled means for permitting the electro-magnetic means to assume said circuit opening position and simultaneously rendering said heating unit ineffective to expand said heat-controlled means.
11. In an electric light system, a light circuit; an electro-magnetic device for closing said circuit; a secondary circuit for said electro-magnetic device; an electric heating unit connected in the secondary circuit with the electro-magnetic device; means for temporarily closing said secondary circuit to cause the electro-magnetic device and the heating unit to function; means operated by said electro-magnetic device for closing said secondary circuit independently of said temporary circuit closing means therefor; means operated by said electro-magnetic device for closing said light circuit; heat-controlled means influenced by said heating unit and controlling by its expansion and contraction the lighting period; and means for causing said light circuit to be opened during and controlled by the contraction of the heat-controlled means.
12. In an electric light system, a light circuit; an electro-magnetic device for closing said circuit; a secondary circuit for said electro-magnetic device; an electric heating unit connected in the secondary circuit with the electro-magnetic device; means for temporarily closing said secondary circuit to cause the electro-magnetic device and the heating unit to function; means operated by said electro-magnetic device for closing said secondary circuit independently of said temporary circuit closing means therefor; means operated by said electro-magnetic device for closing said light circuit; heat-controlled means influenced by said heating unit and controlling by its expansion and contraction the lighting period; means operated by the expansion of the heat-controlled means for closing said light circuit independently of the closing of the circuit effected by the means operated by the electro-magnetic device to permit the electro-magnetic device and the means operated thereby to assume a circuit opening position without opening the light circuit; means operated by the further expansion of the heat-controlled means for permitting the electro-magnetic means to assume said circuit opening position and simultaneously rendering said heating unit ineffective to expand said heat-controlled means; and means for causing said light circuit to be opened during and controlled by the contraction of the heat controlled means.
13. In an apparatus for making and breaking electrical circuits, a heating unit; a heat controlled member influenced thereby; a lever operated by said heat controlled member said lever having two arms one shorter than the other; a lamp circuit; means carried by the longer of said arms for closing and opening said lamp circuit; a secondary circuit; and means carried by the shorter of said arms for closing said secondary circuit said arms being resilient and the contacts being so arranged that both circuits may be maintained closed by said long and short arms at the same time.
14. In an electric light system; a light circuit; an electro-magnetic device for closing said light circuit; an electric heating unit connected with said electro-magnetic device; heat-controlled means controlling by its expansion and contraction the lighting period; means operated by said heat-controlled means for closing said light circuit independently of the closing of the circuit effected by said electro-magnetic device to permit the electro-magnetic device to assume a circuit opening position without opening the principal light circuit; means for causing the circuit to be opened during and controlled by the contraction of the heat controlled means and a magnetic blow out to blow out the arcs resulting from the opening of said circuit.
